UNITED STATES PATENT OFFICE.

DOUGLAS DOBBINS, OF SHELBYVILLE, INDIANA, ASSIGNOR OF ONE-HALF TO JOHN DAY
DE PREZ, OF SHELBYVILLE, INDIANA.

AIRPLANE.

1,336,946.

Specification of Letters Patent. Patented Apr. 13, 1920.

Application filed October 25, 1918. Serial No. 259,667.

To all whom it may concern:

Be it known that I, DOUGLAS DOBBINS, a citizen of the United States, and a resident of Shelbyville, county of Shelby, and State 5 of Indiana, have invented a certain new and useful Airplane; and I do hereby declare that the following is a full, clear, and exact description thereof, reference being had to the accompanying drawings, in which like 10 numerals refer to like parts.

This invention relates to air-planes, and the object of the invention is to assist air-planes in rising and particularly in landing, by enabling them to rise more quickly 15 and more nearly vertically and to descend more slowly and more nearly vertically in landing.

It is known in aeronautics that until an air-plane has attained a high velocity, if the 20 engine stops, the plane will fall, for there is in the air-plane of today no means for preventing or checking its fall. Also often when the plane makes a quick turn and assumes a position more or less on edge and 25 the engine stops, there is difficulty in righting the plane and, if that cannot be done, it will fall. This invention in such emergency may enable the plane to be righted, but, if not, it will act as a "brake" and retard the 30 fall so as to avoid injury.

It is also well known that a great danger in the use of air-planes is due to the difficulty in landing. When the air-plane is under good control, it sometimes strikes the 35 surface of the ground with considerable force, so that the occupants must jump for their lives, and the jar and shock to the machine is very severe upon it. If the ground is rough this danger is all the greater. The 40 chief advantage expected of this invention is to relieve the air-plane from any shock, and enable it to descend very slowly and alight on the ground without any jar to it or discomfort to the occupants of the air-plane, 45 and so that the occupants will not have any fear about the landing, or be compelled to jump for their lives as the air-plane strikes the ground. A minor advantage of the invention is that the air-plane can be started 50 and landed in a much smaller field than without said invention, as it can both rise and descend at a sharper angle.

The chief feature of the invention consists in the combination with an air-plane hav-

ing the usual propelling means, of a plurality of emergency or auxiliary propellers with independent means for driving them when desired, so that when in substantially horizontal positions, they will facilitate the ascent or retard the descent. 55

Another feature of the invention consists in combining with the air-plane and auxiliary propellers, compressed air apparatus for utilizing compressed air to drive the auxiliary propellers, all or any of them, as desired. 60

The full nature of this invention will be understood from the accompanying drawings and the following description and claims. 70

In the drawings Figure 1 is a front elevation of the air-plane equipped with said improvement. Fig. 2 is a side elevation thereof. Fig. 3 is a plan view thereof. Fig. 4 is an elevation of the means for controlling 75 the operation of the auxiliary propellers, parts being broken away. Fig. 5 is an elevation of one of the auxiliary propellers and means for maintaining and driving same, on a larger scale, parts being broken away. Fig. 6 is a plan view thereof. Fig. 7 is a vertical section through the upper part of what is shown in Fig. 5 on line 7-7 of Fig. 6. Fig. 8 is a horizontal section through one of the rotary engines for driving 80 the auxiliary propeller, on line 8-8 of Fig. 7.

There is shown herein a two strutter bi-plane of common type for the purpose of explaining this invention, but the invention 90 is not limited to any particular form of air-plane. In the form shown there is a body 10 with a pilot cock pit 11 and an observer's cock pit 12. There is also a vertical propeller 13 for driving the air-plane and a 95 pair of landing wheels 14 supported by a pair of frames 15 extending down from the body of the air-plane, as shown in Figs. 1 and 2. There is also on each side a lower plane 16 and an upper plane 17. The said 10 airplane is provided with all the other requirements of construction not heretofore specified which are necessary to fully construct and operate the same, but such other details of construction are not given here as 10 they constitute no necessary part of the present invention.

The plurality of horizontally disposed

auxiliary propellers 20 are mounted in connection with the air-plane in any position and manner desired, which will enable them to operate substantially at a right angle to the main propeller 13, so that when the auxiliary propellers operate they will tend to lift the plane. In the drawings herein, four of these auxiliary propellers are shown located above the upper plane 17, but the invention is not limited to the number or position of said propellers.

Each auxiliary propeller is rotatably mounted on a stationary tube 21 which is shown herein as and may be an extension of a vertically disposed strut connecting the two planes, but this arrangement is not necessary, although it simplifies and makes more compact the construction, and it also distributes the auxiliary propellers as indicated in Fig. 3, two of the propellers being near the outer ends and front edge of the upper plane and the other two auxiliary propellers being near the inner ends and rear edge of the upper plane. This enables the propellers to be spaced apart so that they will not interfere with each other and will distribute their action or influence to the air-plane when they are all operating.

The means for driving the auxiliary propellers in the form herein shown, is compressed air, as compressed air apparatus is light and will not overload the air-plane. For that purpose a compressed air tank 25 is provided and it may be secured at any desired position where it is least in the way, or as herein shown strapped to the under side of the body 10 between the wheel supporting frames 15. This tank need not be very large, as all that is required is sufficient compressed air to be used for landing, or for ascending and landing. That would be a very few minutes use in a flight as it would be used only while rising to a position above the trees, buildings and other adjacent structures and during the latter portion of the descent. A pipe 26 leads from the compressed air tank to the instrument plate 27 in front of the pilot or to a board in front of the observer for him to operate if that be preferable. From the pipe 26, branch pipes 28 lead to each supporting tube 21 of each auxiliary propeller. A valve 29 is located in the pipe 26 for starting and stopping the propellers simultaneously and for controlling their speed. There is also a valve 30 in each of the branch pipes so that the auxiliary propellers may be used separately or in pairs if desired. These branch pipes are mounted on the inside of the upper plane so as not to interfere with the operation of any part of the air-plane. The pipes 21 extending above the upper plane are braced by the braces 31.

The auxiliary propeller is driven herein by a pair of rotary engines to be driven by compressed air. There is one rotary engine below and another above the hub 23 of the auxiliary propeller 20. The casing 35 of each rotary engine is secured to a stationary tube 21 by any suitable means, such as a set screw 36. Within the casing of each rotary engine there is a rotary member 37, mounted so as to rotate on the tube 21, which is round where the auxiliary propeller is mounted, although below the propeller and rotary engine said tube need not be round. The rotary member 37 of each of the rotary engines is secured by bolts 38 to the hub 33 of the propeller so as to transmit power directly thereto. This makes a very strong and durable construction.

The compressed air reaches the rotary engine through by-passes 40 leading from tube 21, and by placing the by-pass of one engine in staggered relation with the other co-operating engine a constant drive is provided. This forms a very compact and positive driving means for the auxiliary propellers, which is desirable in such constructions.

The use has already been indicated. When the air-plane starts to travel or to make its ascent, all of the auxiliary propellers are set in motion so they help lift the air-plane off the ground and enable it to rise at a very sharp angle. This is very convenient, particularly in cramped fields or situations. After the air-plane has risen high enough to satisfy the pilot, he can stop the auxiliary propellers and depend on the main propeller and planes to effect a further ascent or can shut off the auxiliary propeller on each side at a time to cause a gradual change in the elevation of the airplane. While descending at any elevation the pilot can start all the auxiliary propellers at full speed so that they will tend to lift the air-plane and serve as a brake to prevent its rapid descent and thus cause it to go down slowly and alight easily. With this aid in descent it is believed that there will result a very great saving in human life and of injury done to the air-planes while landing.

The invention claimed is:

1. The combination with an air-plane, of a propeller therefor having a hub, a tube on which said propeller and hub are rotatably mounted, a fluid-actuated motor secured on said tube adjacent the hub of the propeller and having a rotary part secured thereto, and means for supplying fluid under pressure to said motor through said tube.

2. The combination with an air-plane, of a propeller therefor having a hub, a stationary tube on which the propeller and hub are mounted, a fluid-actuated motor secured on said tube at each side of said hub

and having a rotating part secured to the hub, and means for supplying fluid under pressure to said motors through said tube.

3. The combination with an air-plane, of
5 a propeller therefor having a hub, a stationary tube on which the propeller and hub are mounted, a fluid-actuated motor secured on said tube at each side of said hub and

having a rotating part secured to the hub, means for supplying fluid under pressure to 10 said tube, and a by-pass leading from said tube to each of said motors for driving them.

In witness whereof, I have hereunto affixed my signature.

DOUGLAS DOBBINS.
